UNITED STATES PATENT OFFICE.

JOHN JAMES WARREN, OF BROWNVILLE, NEW YORK, ASSIGNOR TO HARMON PAPER COMPANY, OF BROWNVILLE, NEW YORK, A CORPORATION OF NEW YORK.

DESIGN FOR WALL-PAPER.

54,152.

Specification for Design.

Patented Nov. 4, 1919.

Application filed August 14, 1918. Serial No. 249,916. Term of patent 14 years.

To all whom it may concern:

Be it known that I, JOHN J. WARREN, a citizen of the United States, residing at Brownville, Jefferson county, New York State, have invented a new, original, and ornamental Design for Wall-Paper, of which the following is a specification, reference being had to the accompanying drawing, forming part thereof.

The figure is a plan view of a piece of wall paper, showing my new design.

I claim—

The ornamental design for wall paper, as shown.

In testimony whereof, I affix my signature in the presence of two witnesses.

JOHN JAMES WARREN.

Witnesses:

EDWARD H. ROORBACH,
CHARLES JEWETT GEORGE.
